UNITED STATES PATENT OFFICE.

AUGUST JAHNKE, OF OSCEOLA, IOWA.

HORSESHOE.

SPECIFICATION forming part of Letters Patent No. 340,879, dated April 27, 1886.

Application filed March 28, 1884. Serial No. 126,027. (Model.)

To all whom it may concern:

Be it known that I, AUGUST JAHNKE, a citizen of the United States, residing at Osceola, in the county of Clark and State of Iowa, have invented a new and useful Horseshoe, of which the following is a specification.

This invention has relation to improvements in horseshoes; and it consists in the peculiar construction of parts, as will be hereinafter more fully set forth and claimed.

The object of the invention is to provide a means to prevent overreaching horses from knocking or pulling off their front shoes.

The invention is illustrated in the accompanying drawing, in which the figure is a perspective view of my improved shoe.

Referring by letter to the accompanying drawing, A indicates a horseshoe, which may be of any ordinary or approved construction, and B indicates my improved attachment. This improved device consists of an upwardly-curved bar extending from the opposite rear ends of the shoe. This curved portion extends above the plane of the shoe, and when

the animal overreaches by his hind leg the 25 said extension will serve as a guard to the front shoe.

I have shown the guard as being formed integral with the shoe; but it is obvious that the said guard may be a separate element and 30 secured to the rear ends of the shoe by screws or other suitable fastening devices.

Having described this invention, what I claim is—

1. As an improved article of manufacture, 35 a horseshoe having an integral rear guard, substantially as specified.
2. A horseshoe having a guard secured to its ends and curved upwardly in rear, substantially as specified.
3. A horseshoe having a guard extending 40 in a transverse plane and secured to its opposite ends, substantially as specified.

AUGUST JAHNKE.
